[57] CLAIM

The ornamental design for camera tripod, as shown.

DESCRIPTION

FIG. 1 is a top and right rear perspective view of a camera tripod showing my new design in a fully closed position;

FIG. 2 is a top plan view thereof;

FIG. 3 is a left side elevational view of FIG. 2;

FIG. 4 is a front elevational view of FIG. 2;

FIG. 5 is a right side elevational view of FIG. 2;

FIG. 6 is a rear elevational of FIG. 2;

FIG. 7 is a bottom plan view of FIG. 2;

FIG. 8 is a top and right-rear perspective view of my new design in a fully open position;

FIG. 9 is a top plan view of FIG. 8;

FIG. 10 is a rear elevation view of FIG. 8;

FIG. 11 is a left side elevational view of FIG. 9;

FIG. 12 is a front elevational view of FIG. 9;

FIG. 13 is a right side elevational view of FIG. 8;

FIG. 14 is a bottom plan view of FIG. 8; and

FIG. 15 is a top and left-rear perspective view of FIG. 8 with the camera platform in the vertical position.
